UNITED STATES PATENT OFFICE.

ELIAS HOXIE, OF RED CREEK, NEW YORK.

THILL-CO尤LING.

SPECIFICATION forming part of Letters Patent No. 254,016, dated February 21, 1882.

Application filed May 2, 1881. (Model.)

To all whom it may concern:

Be it known that I, ELIAS HOXIE, of Red Creek, in the county of Wayne and State of New York, have invented a new and useful Improvement in Thill-Couplings, of which the following is a full, clear, and exact description, reference being had to the annexed drawings, forming part of this specification.

This invention consists of an adjustable brace, secured to the under side of the thill and to the bolt by which the coupling is accomplished, the object being to prevent noise by the rattling of the parts against each other.

In the accompanying drawings, Figure 1 is a perspective view of my improved thill-coupling. Figs. 2 and 3 are detail views, and Fig. 4 is a longitudinal section through Fig. 1.

The brace A is made by reducing one end of a straight piece of iron so as to form a stem, on which is cut a screw-thread to receive a nut, D. The other end of the iron is then split toward the stem, and the prongs thus formed are bent apart in a rectangular or curvilinear shape, and holes are drilled in the ends of the prongs to receive the bolt of the clip, by which the thill is coupled to the axle.

A bracket, B, made of iron, having a hole through the center and a screw-threaded stem, is secured to the under side of the thill-iron C, so as to project downward at right angles thereto. If desired, the bracket may be welded

to the thill-iron instead of being inserted in a perforation therein.

The stem of the brace A is inserted into the perforation in the bracket, and its perforated prongs are secured to the clip E by means of its bolt. The nut D is then screwed against the bracket B, so as to exert pressure upon the bolt of the clip, thereby holding the several parts to prevent rattling. The nut D is to be 40 screwed up to take up wear when necessary.

Having thus described my invention, what I claim as new, and desire to secure by Letters Patent, is—

1. The combination, with a thill-coupling, of an adjustable brace secured to the thill and connected to the bolt of the coupling, substantially as shown and described, and for the purpose set forth.

2. The brace A, having a threaded stem at one end and perforated prongs at the other, in combination with a nut, D, screwed on said stem, a bracket, B, for holding said stem, the thill-iron C, and the bolt of the coupling-joint, substantially as shown and described, where- 55 by the brace may be adjusted to take up wear, as set forth.

ELIAS HOXIE.
